MOTOR-SCOOTER

Pier Luigi Torre, Milan, Italy

Application June 18, 1952, Serial No. 20,252

Term of patent 7 years

(Cl. D90—8)

Fig. 1 is a side view of a motor-scooter, showing my new design,

Fig. 2 is a view of the same taken from the front, and

Fig. 3 is a top plan view of the frame of the motor-scooter.

The dominant features of my design reside in the portions shown in full lines.

I claim:

The ornamental design for a motor-scooter, as shown and described.
